AIR GUIDING TRIM CHUTE

Gerald W. Karr, West Chester, Pa., assignor, by mesne assignments, to Beloit Eastern Corporation, Downingtown, Pa., a corporation of Delaware

Filed Mar. 23, 1964, Ser. No. 353,900

6 Claims. (Cl. 83—98)

The present invention relates to improvements in web slitters and particularly to a slitter for trimming a strip from the edge of a travelling web.

Presently used trim slitters generally embody an upper slitter knife with a lower slitter band and require a deflector coming in from above the web to direct the trimmed strip downwardly into duct work to carry the trimmed strip away. At higher speeds and when beginning the trimming operation the trimmed strip tends to bunch up against the deflector and efforts to prevent this, such as providing a highly polished surface on the deflector, have not proven entirely satisfactory. Efforts to carry the trimmed strip away by pulling it downwardly faster than the web speed have required the provision of a support under the trimmed strip at the location where it is being cut to prevent tearing of the web ahead of the slitting point. This usually consists of a rotating hub of the same outer diameter as the slitting band and the hub is usually carried on the shaft of the band. Speed and weight limitations prevent using a hub of not more than approximately two inches in width which cannot handle trim widths of more than four inches.

Accordingly it is an object of the present invention to provide an improved trim slitter which avoids the disadvantages of the prior art, and which insures uniform and proficient carrying away of the trimmed edge without danger of bunching both at high speeds and at starting.

Another object of the invention is to provide an improved trim slitter which avoids the necessity of providing a rotating hub outside of the slitter band and yet does not permit tearing of the web ahead of the slit and which provides advantages over the supporting rotating hub arrangement in that it permits trimming edges of much wider width than heretofore possible.

A further object of the invention is to provide a means for handling and carrying away the trimmed edge of a web in a trim slitter which does not encumber the normal operation of the trim slitter and which permits axially shifting the upper slitter knife axially outwardly away from the band and maintains the space clear which is required for this shifting movement.

A still further object of the invention is to provide a trim slitter which is capable of operating at high speeds without tearing the web ahead of the slitter and avoids the provision of the supporting hub or dummy band with the air cushion which it creates at high speeds raising the edge of the web and avoiding the extra weight which it creates on the slitter band shaft.

A still further object of the invention is to provide an improved trim slitter which provides for easier threading of the web on start-up, eliminates flutter caused by air film on rotating trim supports, provides cleaner and straighter edges on the slits and improved ends on wound rolls, requires no relocating when the trim width is changed and avoids cumbersome overhead or other unnecessary mounting structure, and reduces the friction surfaces in the path of the trim providing a unit which is long wearing and reliable.

A feature of the invention is to provide a web slitter for trimming a strip from the edge of a travelling web including an upper circular slitter knife, a lower slitter band coacting with the knife and a trim strip chute having a lower plate with a first horizontal surface portion out-

2

wardly of the slitters below the slitter knife to permit its being axially shifted outwardly, and having another surface portion curving downwardly of the path of the web with air jets in its surface for directing a flow of high velocity air into the space between the surface and the trimmed strips so that the strip will be controllably held to follow a cushion of air along the surface.

Other objects, advantages and features will become more apparent with the teaching of the principles of the present invention in connection with the disclosure of the preferred embodiment thereof in the specification, claims and drawings, in which:

FIGURE 1 is a somewhat schematic side elevational view showing a slitter mechanism embodying the principles of the present invention;

FIGURE 2 is a front elevational view of the mechanism of FIGURE 1 with parts broken away for clarity;

FIGURE 3 is an enlarged detailed side elevational view of the trim chute of the mechanism of FIGURE 1;

FIGURE 4 is a sectional view taken substantially along line IV—IV of FIGURE 3; and

FIGURE 5 is a top plan view of the chute of FIGURE 3.

As shown on the drawings:

FIGURES 1 and 2 show a travelling web W having an edge T trimmed from the web. For slitting and trimming the edge T from the web W an upper circular slitter knife 10 is positioned above the web coacting with a lower slitter band 11. The trimmed strip T passes down into a chute 12. The trimmed web W continues onwardly over a guide 13 to a winder drum 14 to be wound on a roll 14a.

The slitter band 11 is driven by a direct drive motor 16 and the trim chute 12 is mounted on the motor framework including brackets 17. Thus the trim chute 12 will be positioned in accordance with positioning of the slitter band 11.

The slitter knife or blade 10 is provided with mechanism for moving it axially outwardly independent of the band, the mechanism being shown schematically by the arrowed line 10a, FIGURE 2. The present arrangement provides a support for the trim strip and is below the lower edge of the slitter blade 10 so that the slitter blade will clear the mechanism as it is moved axially outwardly, and this has heretofore been impractical in other mechanisms such as supporting hubs which were required to support the trim strip at the plane of the web, so that the blade could not be shifted axially outwardly. Because of improved control, lack of flutter etc., the present support can be below the blade without the web tearing back of the slit.

FIGURES 3 through 5 show the mechanism for supporting and removing the trim strip T including the trim chute 12.

The trim chute 12 includes a support plate with separate support plate portions.

A horizontal plate portion 18 supports the trim strip as it enters the cutting area and the plate portion 18 has a recess 19 formed in one side to accommodate the slitter band which projects up from the edge of the recess and is located relatively close to the inner edge 19a of the recess 19. The plate portion 18 has an area 18a which is positioned in advance of the slitter blade and band and supports the web, and it also doctors the turbulent air from the web.

When the trim strip is cut from the edge of the web a horizontal plate portion 18b supports the web as it continues its travel to the winder.

Following the slitting of the strip, on the off running side of the slitters 10 and 11, the plate curves downwardly and a plate portion 20 leads downwardly out of the path of travel of the web W.

The downwardly curved plate portion 20 and the horizontal plate portion 18 have a series of air jet openings 24 in the surface adjacent the inner edge of the trim strip T. These jet openings 24 are provided with a high velocity stream of air so that the air will spread out in a cushion below the trim strip and support the strip as it passes downwardly to the lower open end 27 of the chute. While one row of jets are shown, with wide trims, a plurality of rows should preferably be provided. The plurality of rows would be provided by a plurality of manifolds each with jets, extending in parallel rows. For example, in widths of trim over four inches an additional row of jets should be provided on about two inch centers. The high velocity air upon entering the zone below the trim strip spreads out to drop in velocity creating an area of reduced pressure so that the atmospheric air above the strip tends to hold it against the plate portions 18 and 20. This is a significant feature of the arrangement which is provided. This will cause the strip to closely and accurately follow the curvature of the downwardly extending surface of the plate portion 20, preventing flutter and preventing loss of control of the strip.

Protection may be provided over the top of the strip such as by completing the chute with sides 22 and 23 and a top 21. The chute is provided with suitable mounting brackets and is supported on the motor frame as above described. In some instances where the slitter band may be used with a pipe slitter where the band is mounted with other bands on a single shaft, it may be desirable to provide support mechanism for carrying the chute 12 from another location.

For supplying high velocity air to the jet openings 24, a manifold 25 is provided beneath the lower surface of the plate portions 18 and 20. This is conveniently done by slitting a length of tubing and securing the edges of the slit half of the tubing to the undersurface of the plate portions 18 and 20 with the end of the tubing being closed. At the entry end, the tubing is provided with an air connection fitting 26 for supplying air. The jets are preferably directed at an angle in the direction of travel of the trim strip in an angle (FIGURE 3) of substantially 30° with the normal to the web has been found satisfactory.

As previously stated, the upper surface of the plate portion 18 is slightly below the lower edge of the slitter knife 10 with the slitter knife being axially movable over the surface 18.

In operation, the slitter knife 10 and slitter band 11 are set axially to provide a trim strip of the desired width relative to the web W, and air is directed to the manifold 25 to be emitted from the jets 24. As soon as the web passes through the slitters and the strip is out from the edge it will follow down along the surface portions 18 and 20 without danger of gathering or jamming. The strip is uniformly drawn away without flutter reducing the chance of the web tearing ahead of the location where it is cut by the slitters. The present arrangement works fully as well at high speed operations as at low speed, and heretofore speeds on the order of 2,000 feet per minute have been considered to be as high as practical, but with the present arrangement speeds on the order of 5,000 feet per minute are accomplished without difficulty.

The air jet openings are preferably $\frac{1}{2}$ inch in diameter and the upper curvature of the plate portion 20 is preferably swung about an arc having its center 28 slightly outside of (to the right as shown in FIGURE 3) the center 27 of the lower slitter band, such as on the order of $\frac{1}{4}$ inch. The surfaces 18 and 20 should be smooth and brightly polished although this is not as critical as with structures heretofore used inasmuch as the air cushion will positively control and support the trim strip.

For aiding in holding the web in position, means are provided for removing air from the surface of the lower slitter band 11 such as by a curved doctor blade 15, FIGURE 1. This is a significant feature of operation since the air on the band 11 is turbulent and its removal is very advantageous.

It is also a feature of the present invention for the area 18a of the plate portion (and particularly the leading edge thereof) to doctor air from the lower surface of the web W. There is considerable volume of turbulent air travelling with the web which normally causes undesirable flutter when the air combines with the turbulent air travelling with the slitter band and/or the rotating trim support. The leading edge of the area 18a of the plate portion eliminates this flutter by removing the air from the sheet surface.

Thus it will be seen that I have provided an improved trim slitter arrangement which meets the objectives, advantages and features above set forth. The unit is well suited for use in trimming the edge of a travelling paper web and is capable of handling webs of substantially any width or weight and may be used with different types of webs. The web does not tear ahead of the slitting point and the resistant friction in the path of the trim has been eliminated.

The drawings and specification present a detailed disclosure of the preferred embodiments of the invention, and it is to be understood that the invention is not limited to the specific forms disclosed, but covers all modifications, changes and alternative constructions and methods falling within the scope of the principles taught by the invention.

I claim as my invention:

1. A web slitter for trimming a strip from the edge of a travelling web comprising in combination, an upper circular slitter knife, a lower slitter band coacting with the knife for trimming the outer edge from a travelling web, a trim strip member having a surface outwardly of the slitters extending out of the path of the web for carrying away the trimmed strip, means directing a flow of high velocity air into the space between said surface and the trimmed strip so that the strip will be controllably held and guided along the surface, and doctor means having a doctoring edge doctoring an air film from the surface of the slitter band.
2. A web slitter for trimming a strip from the edge of a travelling web comprising in combination, first and second slitter members for slitting and trimming an outer edge from a travelling web, said slitter members overlapping to form a cutting zone, an arcuate control member having a surface curving away from the slitter members out of the path of the web, means defining openings in said surface, and means for directing a flow of air through said openings between the surface and the trimmed strip, said flow of air being present at the cutting zone.
3. A web slitter for trimming a strip from the edge of a travelling web comprising in combination, an upper circular slitter knife, a lower slitter band coacting with the knife for trimming the outer edge from a travelling web, said slitter members overlapping to form a cutting zone, a trim strip guide member having a surface outwardly of the slitters extending out of the path of the web for carrying away the trimmed strip, and a plurality of air jets opening between the strip and the surface directed at an angle to said surface in the direction of movement of the strip, said air jets being present at the cutting zone.
4. A web slitter for trimming a strip from the edge of a travelling web comprising in combination, first and second slitter members for setting and trimming an outer edge from a travelling web, said slitter members overlapping to form a cutting zone, a guide plate outwardly of the slitter members turning out of the path of the web with an upper surface facing the trimmed edge strip, a plurality of jet openings in the surface of said plate, said openings being present at the cutting zone,

an elongate manifold extending along the back of the plate communicating with said openings, and means delivering air to said manifold to be emitted from the openings and supportingly hold the strip to follow the surface.

5. A web slitter for trimming a strip from the edge of a travelling web comprising in combination, an upper circular axially-movable slitter knife, a lower circular slitter band, a direct drive motor for the band, means receiving the web from the slitters after an edge is trimmed therefrom,

a rectangular shaped trim chute on the off running side of said slitters having a lower support surface extending out of the path of the web with a first horizontal portion parallel to the path of the web and a second curving portion extending downwardly, said first portion of said support surface being below the slitter blade to permit axial movement of the blade over the surface,

20 a plurality of openings in said surface arranged in a row substantially parallel to the path of travel of the web,

a split tube manifold on the under surface of the chute attached thereto communicating with the openings, said openings extending for an angle of substantially 30° to a line normal to the support surface and extending generally in the direction of travel of the trimmed strip, said chute supported on said motor,

means for delivering a flow of high velocity air to said manifold,

a doctor member having a doctoring edge in advance of the on running side of said knives positioned for removing air from the surface of the slitter band, and

10
15

5. a travelling web comprising in combination, slitter means for slitting and trimming an outer edge from a travelling web travelling along a first path, said slitter means forming a cutting zone, said edge travelling along a second path out of the first path after being slit, and at least one row of air jets extending along said second path for directing a flow of air along the surface of the edge providing a position controlling air film support therefor, said air jets being present at the cutting zone.

a plate attached to said chute extending horizontally beneath the web parallel to the web supporting the web after the strip is trimmed therefrom.

6. A web slitter for trimming a strip from the edge of

5 a travelling web comprising in combination, slitter means for slitting and trimming an outer edge from a travelling web travelling along a first path, said slitter means forming a cutting zone, said edge travelling along a second path out of the first path after being slit, and at least one row of air jets extending along said second path for directing a flow of air along the surface of the edge providing a position controlling air film support therefor, said air jets being present at the cutting zone.
